DESIGN FOR A DRESS

Philip Heit, New York, N. Y.

Application October 10, 1934, Serial No. 53,535

Term of patent 3½ years

To all whom it may concern:

Be it known that I, PHILIP HEIT, a citizen of the United States of America, residing in Manhattan, county of New York and State of New York, have invented the new, original, and ornamental Design for a Dress, of which the following is a specification, reference being had to the accompanying drawing, forming part thereof, wherein,

I claim:

The ornamental design for a dress, substantially as shown.

PHILIP HEIT.
